FOREIGN PATENT DOCUMENTS

JP 2006289028 A2 10/2006

Primary Examiner—Robert M Spear*Assistant Examiner*—Karen Acker(74) *Attorney, Agent, or Firm*—Peter D. Meyer(57) **CLAIM**

The ornamental design for a carton, as shown and described.

DESCRIPTION

FIG. 1 is a perspective view of the carton embodying my new design;

FIG. 2 is a top planar view, the bottom planar view being a mirror image thereof;

FIG. 3 is a front elevational view, the rear elevational view being a mirror image thereof;

FIG. 4 is a side elevational view thereof; and,

FIG. 5 is the other side elevational view thereof.

The broken lines in the drawings represent unclaimed environmental subject matter.
